(57) CLAIM

The ornamental design for a tray for cotton candy machine, as shown and described.

DESCRIPTION

FIG. 1 is a top front perspective view of a tray for cotton candy machine, showing our new design;

FIG. 2 is a front elevation view thereof;

FIG. 3 is a rear elevation view thereof;

FIG. 4 is a left side elevation view thereof; and

FIG. 5 is a right side elevation view thereof.

FIG. 6 is a top plan view thereof; and,

FIG. 7 is a bottom plan view thereof.

The broken lines show portions of the tray for cotton candy machine that form no part of the claimed design.
